UNITED STATES PATENT OFFICE.

CHAUNCEY B. FORWARD, OF URBANA, OHIO.

APPARATUS FOR VAPORIZING HYDROCARBON OILS.

1,255,149.

Specification of Letters Patent.

Patented Feb. 5, 1918.

Application filed February 5, 1916. Serial No. 76,376.

To all whom it may concern:

Be it known that I, CHAUNCEY B. FORWARD, citizen of the United States, residing at Urbana, in the county of Champaign and State of Ohio, have invented certain new and useful Improvements in Apparatus for Vaporizing Hydrocarbon Oils, of which the following is a specification.

This invention relates to an apparatus for vaporizing hydro-carbon oils, all substantially as shown and described and particularly pointed out in the claims.

In the accompanying drawings, Figure 1 is a vertical longitudinal sectional elevation of the apparatus, and Fig. 2 is a sectional plan on line 2—2, Fig. 1. Fig. 3 is a cross section substantially on line 3—3, Fig. 1, and Fig. 4 is a front elevation of the complete installation.

The conception herein embraces the apparatus more or less as a whole and details of construction here and there which contribute to its utility and efficiency, it being understood that the primary object of the invention is to so treat the oil in the retort that the largest possible percentage of gasoline may be derived from the vaporized product in such subsequent treatment as may be had by condenser or otherwise.

As herein shown A represents the wall of the furnace and a, b and c the vaporizing sections or parts of the retort proper. The said sections or portions are each double, in a sense, as there is an inner tube or pipe 2 for the oil and an outer tube or pipe 3 forming a jacket about the same for superheated steam. These sections and the inclosing wall of the furnace may have any suitable length, say twenty feet, more or less, and the said sections are set at such inclination in respect to each other as to provide continuous drain or flow by gravity of any possible unvaporized substances through the same. The said sections also are continuous one with the other from a to b and b to c by means of elbows or joints d and d' at their ends, but the said elbows or joints are exposed outside the wall A and connect only the oil tubes 2 and not the superheated

steam jackets 3, as seen more especially in Figs. 1 and 2. That is, the elbow or joint d at the rear connects the upper oil pipe section with the pipe 2 in section b, and the elbow or joint d' connects the two lower sections or pipes 2, the latter of these discharging at 5 at the rear of the retort. From this point the vapors are taken off for subsequent treatment in condensers or the like. The said elbows also are removable so as to make it possible to reach and remove any one of the pipes 2 without disturbing other parts.

It will be noticed that the outer or jacket pipes 3 of the said sections terminate substantially at the wall of the furnace, and have annular flanges or rings 6 just outside said wall at their ends which are bolted to a collar 8 sleeved on oil pipe 2, and which collar has a packing gland within the same about pipe 2 and adapted to be tightened by another collar 10 which is adjustably bolted to the packing collar 8 and has a portion bearing against the packing under collar 8 to tighten the same. This provides for unequal expansion and contraction in said pipes or tubes, as unavoidably occurs, and which has to be taken care of in this way to avoid leakage of steam. As to this tendency of the steam to leak it should be understood that the exceedingly high temperatures employed are such that the said retort sections will become red hot. Hence the importance of joints in all the superheating steam channels which are absolutely proof against leakage and will remain so regardless of extreme temperature and pressure. This also makes both the pipes 2 and 3 of each section free to expand without disturbing the packing between them and without leakage, and the outer pipes 3 are facilitated in longitudinal expansion and contraction by rollers 12 on which they rest at their front ends and have free longitudinal movement.

The furnace is shown as heated by means of oil by pipe 9 and superheated steam by pipe 11, and the steam employed in the retort for heating the oil therein flows from the boiler through pipe 15 and the coils 16

therewith in the furnace and which are exposed to the superheating temperatures therein as also are the said retort sections. From these coils the superheated steam flows 5 by the extension of said coil pipe through the side of the furnace wall to the union 17, which is purposely placed outside at this point to enable the coils 16 to be disconnected and removed when for any reason this 10 becomes necessary, and which removal is very liable to become necessary on account of the high heat to which they are subjected.

From the said outside union or joint 17 the pipe returns within the furnace again by 15 connection 19 to joints 20 at the front of the furnace and thence by pipe 21 to the several steam distributing pipes 22, 23, 24 and 25 to the steam jackets of the said several retort sections *a*, *b* and *c*. Each of the 20 three down pipes from pipe 22 to said sections is provided with a hand controlled valve 26, and pipe 22 has a blow-out 26 and a pressure gage 27 surmounts pipe 21.

Oil is supplied to the retort for vaporizing 25 from a head or supply which employs a force pump, not shown, and the oil is driven under the requisite pressure through pipe 30 to a preheater or superheater 31 located over the wall or top of the furnace and 30 running the full length thereof from rear to front. The said superheater has an oil carrying pipe 32 on its inside and a pipe 33 about the same providing a jacket of superheated steam for said oil pipe. The 35 pipe 33 is wrapped heavily with asbestos or the like to confine the heat, and oil flows into the rear end of the superheater by pipe 30, while superheated steam from the rear ends of vaporizing sections *a*, *b* and *c* flows 40 into the jacket 33 of the superheater by pipes 35 and 36.

From the superheater 31 the oil flows to 45 the upper of the several retort sections by pipe 37 through an atomizing nozzle 40 at its front end and superheated steam from 50 the superheater likewise enters the atomizer with the oil by pipe 38 and in such manner as to contribute most effectively to the vaporization and dissemination of the oil vapors with the steam. In fact, however, the oil is not only vaporized in the superheater but the vapors thereof are heated to a very high temperature so that when the oil vapors 55 reach the atomizer 40 and enter the retort with the superheated steam they are in a state to commingle thoroughly therewith, and the said vapors and steam traverse the said retort sections together and issue in a superheated state from section *c* at the 60 exhaust 5 to the condensers or separators next in order.

By building the retort in sections as shown I am enabled to accomplish a large volume

of work in a compact area, and the said sections obtain the maximum exposure together in the furnace, and such exposure or temperature may be very high according to the fuel used. 65

When the vapors reach the discharge at elbow 5 such treatment or disposition thereof may follow as shall be deemed desirable, and obviously, there will be ultimate condensation and separation but the means for this purpose do not constitute a part of this 70 invention. 75

What I claim is:

1. The apparatus described comprising a furnace chamber, a plurality of retort sections in said furnace consisting each of an inner tube for oil and an outer tube for a steam jacket, the said outer tubes terminating with the furnace walls and the inner tubes extending beyond the wall thereof, packing for said outer tubes on said inner tubes and joints connecting the ends of the 80 inner tubes outside the furnace wall.

2. An apparatus as described, comprising a furnace, a plurality of retort sections exposed in said furnace on different horizontal planes and having inner oil tubes and outer superheating jackets terminating within the ends of the inner tubes, removable tubular joints connecting the ends of said inner tubes outside the wall of the furnace and an atomizer in the end of the upper of 90 95 said sections to inject oil and steam together therein.

3. An apparatus as described, comprising a furnace and a sectional retort therein consisting of oil pipes extending through the 100 walls thereof and steam jackets terminating at said walls having annular flanges at their ends and collars next to said flanges on said oil pipes provided with packing glands, and elbow joints connecting the ends of said oil pipes outside said glands, whereby expansion of said pipes can occur without causing leakage of the steam from said 105 jackets.

4. In an apparatus as described, a plurality of retort sections openly connected at their ends and having steam heating jackets between their ends, in combination with an oil heater having a steam jacket openly connected by separate pipes with the jackets of 110 115 said retort sections respectively.

5. In an apparatus as described, a plurality of retort sections at different elevations and provided with oil carrying tubes open one to the other at their ends and provided with steam jackets between their ends, in combination with a tubular oil heater having a steam jacket about the same and pipes from the jackets of said retort sections discharging into the jacket of said 120 oil heater, and pipe connections from said 125

oil heater and the jacket thereon arranged to discharge together into the upper of said retort sections.

6. In an apparatus as described, a retort consisting of inner and outer tubes spaced apart to form a jacket between them and means providing for unequal expansion of said tubes comprising a packing for the ends of the outer tube about said inner tube

and in which said inner tube is slid able, and 10 rollers supporting the corresponding end of the outer of said tubes behind said packing.

In testimony whereof I affix my signature in presence of two witnesses.

CHAUNCEY B. FORWARD.
